UNITED STATES PATENT OFFICE.

CARL ARNOLD, OF NUERMBERG, GERMANY.

SPARK TOY.

Application filed May 16, 1927, Serial No. 191,788, and in Great Britain October 18, 1926.

This invention relates to a toy and it is distinguished from known models in that, by a spring-controlled rack a toothed-wheel gear-mechanism is operated and a spark producing device arranged above the casing is rapidly rotated, the brushes of sparks produced by the spark-producing device being broken in star-shapes and becoming visible through a glass-pane which covers the spark producing mechanism. In order to make the brushes of sparks produced by the spark-producing mechanism appear at alternating intervals and in different colours, a disk having apertures and transparent elements of different colours is loosely mounted on the shaft of the spark-producing mechanism above the glass-pane. The result of this arrangement is that, by the rotation of the spark-producing mechanism, the disk having coloured transparent elements is rotated at reduced speed from the shaft of the spark-producing mechanism. The spark brushes produced by the spark producing mechanism are visible through the slowly rotating transparent elements of this disk in different colours and arrangements.

An embodiment of the invention is shown, by way of example, in the accompanying drawing in which

Fig. 1 is a side elevation partly in section. Fig. 2 is a top plan view.

In slots of a casing α a rack b is guided which meshes with a pinion d keyed on a vertical shaft c and made in one piece with a spur-wheel f . The vertical shaft c is shiftably mounted in slots of the casing α .

By a pressure exerted upon the outer end of rack b the shaft c , and with the same the pinion d and spur-wheel f is shifted in the slots of the casing, the pinion being rapidly rotated owing to its engagement with the rack, so that the spur-wheel f , when it comes in gear with the pinion g , communicates a rapid rotating movement to this pinion g and to the shaft h of the same. The rack b , when released, is returned into the initial position by the action of a spiral-spring i attached at the one end to the casing and at the other end to said rack. In the casing α one element of a spark-producing mechanism, for instance an emery disk k , is mounted fixed on the casing α , the other element, i. e. a cerium stone l , being fixed to a disk m , adapted to be rotated by shaft h . This disk m has different apertures n through which the brushes of

sparks produced by the friction of the cerium stone l on the emery-disk k can pass. On shaft h a head o is fixed over which a disk p is placed which has several apertures q closed by sheets r of transparent material coloured in different colours.

When the toy is being operated this upper disk p is rotated by the action of the centrifugal force, so that the spark brushes become visible successively through the transparent elements r in slowly changing colours.

A ring s on head o serves to secure disk p in its position.

The operation is as follows:—

By a pressure exerted upon the outer end of rack b the spur-wheel f is brought into engagement with the pinion g which, together with shaft h and the emery disk k and disk m , is rapidly rotated. The disk p with the transparent elements r is much more slowly rotated by virtue of the frictional contact with rotating shaft h , upon which it is loosely mounted. Brushes of sparks are produced by the cerium-stone sliding along the emery-disk k , said sparks passing through the apertures n of disk m , so that they light the transparent elements r . A continuously changing coloured picture is thus produced as the disk m with the cerium-stone rotates rapidly while disk p with the transparent elements r rotates slowly.

I claim:—

1. A toy comprising in combination, a casing having slots in its end walls and slots in the bottom-plate and top-wall, a rack mounted in the slots of the end-walls and projecting from said casing, a pull-spring attached at the one end to said casing and at the other end to the inner end of said rack, a gear-wheel transmission operated by the inward movement of said rack and shiftably mounted in said slots of the bottom and top plates, a spark-producing mechanism rapidly rotated by said gear-wheel transmission, a vertical shaft, a head at the top end of said shaft, a disk having apertures covered with differently coloured transparent elements and loosely mounted on said head so that it is slowly rotated by friction said sparks becoming visible at certain intervals and in different colours through said transparent elements, and a disk covering said spark-producing mechanism and having apertures through which the sparks pass which are produced.

2. A toy comprising in combination, a cas-

ing having slots in its end walls and slots in the bottom-plate and top-wall, a rack mounted in the slots of the end-walls and projecting from said casing, said rack being known 15
5 per se a pull-spring attached at the one end to said casing and at the other end to the inner end of said rack, a gear-wheel transmission operated by the inward movement of said rack, and consisting of a vertical shaft
10 shiftably mounted in said slots of the bottom and top plate of said casing, of a pinion keyed on said shaft and engaging with said rack, and of a spur-wheel of great diameter rigid with said pinion, a spark-producing mechanism rapidly rotated by said gear-wheel transmission, and a disk covering said spark-producing mechanism and having apertures through which the sparks pass which are produced.

In testimony whereof I affix my signature.

CARL ARNOLD.
